UNITED STATES PATENT OFFICE.

JOHN A. MONTGOMERY, OF BIRMINGHAM, ALABAMA.

COMBINED LEVELER AND SWEEPER FOR COKE-OVENS.

SPECIFICATION forming part of Letters Patent No. 579,160, dated March 23, 1897.

Application filed August 17, 1896. Serial No. 559,661. (No model.)

To all whom it may concern:

Be it known that I, JOHN A. MONTGOMERY, a citizen of the United States, residing at Birmingham, in the county of Jefferson and 5 State of Alabama, have invented a certain new and useful Improvement in a Combined Leveler and Sweeper for Coke-Ovens; and I do hereby declare the following to be a full, clear, and exact description of the invention, 10 such as will enable others skilled in the art to which it appertains to make and use the same.

My invention relates to an improvement in a combined leveler and sweeper for coke-ovens, 15 and has for its object to quickly level the coal therein and after the coal has been converted into coke and the coke removed to thoroughly sweep and clean the oven, and also to provide a machine which is simple and inexpensive 20 in construction and very effective in operation.

My invention consists in the construction and arrangement of the several parts, as more fully hereinafter described and specifically 25 claimed.

In the accompanying drawings, in which like letters of reference designate like parts in all the views, Figure 1 is a sectional view of a coke-oven, showing a side elevation of 30 my improved leveler and sweeper therein, the leveler being applied in full lines and the sweeper applied as shown in dotted lines. Fig. 2 is a top plan view with the leveler applied; Fig. 3, a detail front view, partly in 35 section, of the sweeper and its operating mechanism and the locking-bolt by which the sweeper is adjusted and held at different angles; Fig. 4, a diagram showing different positions of the sweeper; and Fig. 5, a horizontal section of sweeper, showing the mechanism for locking the sweeper at different 40 angles.

In the drawings, A represents the coke-oven, preferably of the well-known beehive construction.

B represents the frame of the apparatus, composed of hollow tubes or pipes a b, made preferably plain on its under side for the purpose of adapting it to be readily manipulated 45 on a suitable support situated in the door of the coke-oven. At one end these pipes ter-

minate in a handle c, by means of which the apparatus is manipulated in any desired direction, and at the opposite end terminate in a hollow slotted elbow d.

55

e is a sprocket-wheel which is mounted on the shaft f and the cogs of which extend into the slot in the elbow d, and e' is a sprocket-wheel mounted on the drive-shaft f'.

g g' are bearings for the sprocket-wheels 60 e e', respectively.

h is an endless sprocket-chain which runs inside the pipes a b (for the purpose of keeping it from being clogged with dirt, &c.) and over the sprocket-wheels.

65

A series of grooved antifriction-rollers i are mounted at intervals in the journals j, formed by cutting the pipes and bending the cut portions outward.

k is a crank-arm mounted on the end of the 70 drive-shaft f'.

l is a platform mounted on the pipes a b.

M is a suitable engine mounted on said platform, such, for instance, as a hydraulic, steam, electric, or other engine.

75

n is the drive-rod of the engine, which is connected to a pin o on the crank-arm k.

p is a flexible feed-water pipe for the engine.

C is the leveler, which is provided with a 80 shaft q, having a socket q' and set-screw q² at its upper end, by which it is attached to the shaft f' of the apparatus.

85

q³ are scrapers, and q⁴ are rakes attached to the hub q⁵ at the lower end of shaft q.

The leveler is shown in the drawings with both scrapers and rakes; but when desired the rakes may be dispensed with and all scrapers used or the scrapers dispensed with and all rakes used.

90

D is the sweeper, provided with a shaft q⁶, connected to the shaft f by means of a double screw-threaded nut q⁷.

q⁸ is a bevel gear-wheel on the lower end of shaft q⁶.

95

q⁹ is a hub or sleeve provided with circular collars q¹⁰ and groove q¹¹.

q¹² are holes in the slot q¹¹.

q¹³ are arms depending from a circular ring q¹⁴, which rotates in the groove q¹¹ and is held at any desired point by means of a spring-pressed pin q¹⁵ engaging the holes q¹².

100

q^{12*} is a chain or rope for operating spring-pin q^{15} .

q^{16} is a circular broom having a shaft q^{17} , mounted in bearings q^{18} on the lower end of 5 the arms q^{13} .

q^{19} is a bevel gear-wheel adapted to engage the bevel-gear q^8 and be operated thereby.

q^{20} are wheels located on the extreme lower end of the arms q^{13} , on which the sweeper is 10 supported and moved.

E is an antifriction-roller which extends across and is journaled at each end in the sides of the door-frame, on which the apparatus rests and travels when the leveler is 15 used.

The apparatus may be operated in any direction and the sweeper turned to any angle at the will of the operator.

The operation is as follows: The coke-leveler is inserted through the door of the oven and rests and travels on the antifriction-roller E , which extends across and is removably journaled at each end in the door-frame. The leveler commences to work on the side 25 of the cone-shaped pile of coal, and by its circular motion quickly levels the coal to a uniform level, as shown by the dotted line 1 in Fig. 1. After the coal has been leveled the roller E is removed and the apparatus with- 30 drawn from the oven. The coal is then converted into coke and the coke removed by any suitable means. The sweeper is then attached and the apparatus again inserted in the oven and the sweeper worked around, as 35 shown at x , until the small coke and ashes have been thrown to the center. Then the sweeper is changed to the right angle, as shown at x' , Fig. 4, and the apparatus withdrawn from the oven, sweeping and carrying 40 the material with it through the door to any suitable receptacle.

Having thus described my invention, what I claim is—

1. In a portable leveler and sweeper for 45 coke-ovens, the frame having a plain under surface, and provided on one end with suitable motive power, and on the opposite end with a depending shaft adapted to carry a leveler or sweeper thereon, and means for 50 communicating motion from said motive power to said shaft, substantially as described.

2. In a portable leveler and sweeper for coke-ovens, the frame having a plain under 55 surface and provided on one end with suitable motive power, and on the opposite end with a depending shaft adapted to receive a leveler to level the coal in the oven, and a sweeper to sweep out the oven after the coal has been 60 converted into coke and removed therefrom, and means for communicating motion from

said motive power to said shaft, substantially as described.

3. In a portable leveler and sweeper for coke-ovens, the frame having a plain under 65 surface and composed of hollow tubes or pipes, provided on one end with suitable motive power, and on the opposite end with a depending shaft adapted to receive a leveler to level the coke in the oven, and a sweeper 70 to sweep out the oven after the coal has been converted into coke and removed therefrom, and means for communicating motion from said motive power to said shaft, substantially as described.

4. In a portable leveler and sweeper for coke-ovens, the frame having a plain under surface, and composed of hollow tubes or pipes provided with a series of antifriction-rollers, sprocket-wheels mounted on shafts at 80 opposite ends thereof, and the sprocket-chain adapted to run inside of hollow tubes and over the sprocket-wheels and antifriction-rollers, one of said shafts connected to a suitable motive power by which it is driven, and 85 the other shaft depending from said frame, and adapted to receive a leveler to level the coal in the oven, and a sweeper to sweep out the oven after the coal has been converted into coke and removed therefrom, substan- 90 tially as described.

5. In a portable leveler and sweeper for coke-ovens, the frame having a plain under surface, and provided on one end with suitable motive power, and on the opposite end 95 with a depending shaft, the leveler mounted thereon and means for communicating motion from said motive power to said depending shaft, substantially as described.

6. In a portable leveler and sweeper for coke-ovens, the frame having suitable motive power on one end thereof, and the opposite end provided with a depending shaft, the sweeper mounted thereon, means for communicating motion from said motive power to 105 said shaft, and means for setting said sweeper at different angles, substantially as described.

7. In a portable leveler and sweeper for coke-ovens, the frame having suitable motive power on one end thereof, and the opposite 110 end provided with a depending shaft, the sweeper mounted thereon, means for communicating motion from said motive power to said depending shaft and thereby operating the sweeper, substantially as described. 115

In testimony whereof I affix my signature in presence of two witnesses.

JOHN A. MONTGOMERY.
